UNITED STATES PATENT OFFICE.

ALFRED N. SILL, OF PHILADELPHIA, PENNSYLVANIA.

BLOTTER.

SPECIFICATION forming part of Letters Patent No. 296,235, dated April 1, 1884.

Application filed April 14, 1883. (No model.)

To all whom it may concern:

Be it known that I, ALFRED N. SILL, a citizen of the United States, and a resident of Philadelphia, Pennsylvania, have invented improvements in Blotters, of which the following is a specification.

My invention consists of an improved handled blotting-pad with a flexible blotting-surface, as more fully described hereinafter.

- 10 In the accompanying drawings, Figure 1 is a perspective view illustrating one form of my improved blotting-pad and the manner of using the same; Fig. 2, a longitudinal section; Figs. 3 and 4, enlarged sectional views 15 of the spring-clamps, Fig. 3 showing a clamp open, and Fig. 4 showing the opposite clamp closed; Fig. 5, a longitudinal section of a modified form of blotter, and Fig. 6 a sectional view illustrating another modification.
- 20 A is a curved spring-plate of sheet metal of suitable dimensions, and to the concave back of this plate is secured with yielding connections, as hereinafter described, a handle, B, whereby the blotter may be conveniently manipulated.

25 To the convex side of the plate are applied a series of sheets, D, of blotting-paper, cut to the proper size and placed one above the other to form the blotting-surface. These blotting-sheets are held in place by spring-clamps E—one secured to each end of the plate A—as illustrated more fully in the enlarged views, Figs. 3 and 4. Each end of the plate A is bent backward to form a hook, a, with which engages the hooked end b of the clamp-plate, a portion, d, of the latter bearing against the edge of the plate A, and, being of spring sheet metal, it maintains the two hooks a b in proper engagement with each other. The 30 clamping-plates E, thus hung to the plate A, can be adjusted to either the open position shown in Fig. 3, to allow the blotting-sheets to be put in place, or to the closed position shown in Fig. 4, to retain the ends of the sheets, and the 35 spring-clamps will be self-retaining, in either of the positions, against accidental displacement. I prefer to make the clamping-plates of about the same width as the plates A, and I provide each with a handle, f, to facilitate 40 the opening and closing of the clamp, and for convenience I prefer to form this handle by

striking or bending up a portion of the plate E itself, as illustrated in Fig. 1. No joints, pins, or other expensive fittings are required in hanging the plates E to the plate A, one 55 plate being simply slipped laterally onto the other in such a position that the hooks a b engage with each other, this engagement of the hooks, in connection with the bearing on the end of the plate, being the only fastening required, so that the blotter can be very economically constructed, and possesses the necessary qualities of strength and freedom from liability to get out of order.

As I have above stated, the handle B is connected to the elastic plate A with a yielding connection, so that when the blotter is pressed down onto the surface to be blotted the spring-plate A is at liberty to straighten itself out over the said surface, as shown in Fig. 1. 60 This yielding connection of the handle with the plate A may be provided at one or both ends of the handle. In the construction shown in Figs. 1 and 2 the handle B is arch-shaped, and on each end is formed a T-head, b', adapted 65 to grooves a' on the plate, formed by bending up sheet-metal strips secured to the plate. The lower ends of these grooves are open, to permit the insertion of the T-heads on the handle when the spring-plate is flattened out. 70 The upper ends of the grooves or slots are closed, and preferably provided with rubber pads h. If preferred, the grooves a' may be formed by cutting a longitudinal slot in each end of the plate and bending the portion of 75 the metal cut from the slot to form a guard, n, to protect the blotting-paper from the T-head on the handle B, as shown in Fig. 5, in which the handle is of a somewhat different form from that shown in Figs. 1 and 2; or, if desired, the slot for the T-head may be formed in a bent strip secured to the plate A, instead 80 of in the plate A itself.

Instead of forming T-heads on the handle adapted to grooves in or on the plate, a projection or pin, r, on the plate may be adapted to an opening in each end of the handle, as indicated in Fig. 6.

The handle may have a yielding connection with the plate at one end, the other being 90 fixed; but I prefer to have both ends free.

By connecting the handle to the plate, as

described, the ends of the plate are unconfined, and it is at liberty to flatten out, as indicated in Fig. 1, when pressure is applied to the handle, so that the rocking movement usually employed with blotters of this class is unnecessary.

Instead of using spring-clamps at each end of the plate A, a hook or permanent clamp may be used at one end of the plate, in connection 10 with a spring-clamp at the other; but I prefer the use of two spring-clamps.

I claim as my invention—

1. The combination of the curved elastic plate A, carrying the blotting-surface, with a handle, B, having a longitudinally-yielding connection with said plate, whereby on pressing the handle downward the plate A is at liberty to flatten out, as set forth.

2. The combination of an elastic plate, A, 20 carrying the blotting-surface, and provided at one or each end with a slot or groove, with a

handle, B, having a T-head adapted to said slot or groove, substantially as described.

3. The combination of a handle and plate, A, with a blotting-surface, and spring-clamps 25 at each end of the plate A, as specified.

4. The combination of a plate, A, having a hooked end, a, with a plate, E, having a hook, b, and bearing d, substantially as set forth.

5. The combination of a sheet-metal plate, 30 A, having a hooked end, a, with the plate E, having a hook, b, and adapted to be applied to the hooked end of the plate A laterally, substantially as described.

In testimony whereof I have signed my name 35 to this specification in the presence of two subscribing witnesses.

ALFRED N. SILL.
